CLAIM

The ornamental design for a notebook laptop computer, as shown and described.

DESCRIPTION

1. Notebook laptop computer

1.1 : Perspective

1.2 : Front

1.3 : Back

1.4 : Left

1.5 : Right

1.6 : Top

1.7 : Bottom

1.8 : Perspective

1.9 : Front

1.10 : Back

1.11 : Left

1.12 : Right

1.13 : Top

1.14 : Bottom

(Continued)

The present ornamental design is a combination of the shape and pattern of a notebook laptop computer as shown and described.

1 Claim, 14 Drawing Sheets
